UNITED STATES PATENT OFFICE.

FRIEDRICH JOHANN DITRICH HÜLLINGHORST, OF LONDON, ENGLAND.

RADIATOR OR COOLER FOR MOTOR ROAD-VEHICLES.

No. 884,929.

Specification of Letters Patent.

Patented April 14, 1908.

Application filed June 24, 1907. Serial No. 380,579.

To all whom it may concern:

Be it known that I, FRIEDRICH JOHANN DITRICH HÜLLINGHORST, a subject of the Emperor of Germany, of 190 Blythe road, 5 West Kensington Park, London, in the county of Middlesex, England, have invented a new and useful Improvement in Radiators or Coolers for Motor Road-Vehicles, of which the following is a specification.

10 This invention relates to radiators or coolers for motor road vehicles whereby the temperature of the water which is circulated about the engine cylinders and other parts of such vehicles to be cooled is considerably reduced and overheating prevented.

15 The present invention has reference more especially to radiators or coolers of this class such as are described in the specification accompanying my application for Letters Patent dated March 13th, 1907, Serial Number 20 362221.

25 Radiators or coolers of the kind above referred to have comprised an air-propelling fan in combination with an annular chamber or chambers and supplemental cooling-spaces arranged at the front and back of the radiator; said chambers and supplemental cooling spaces being furnished with inter-communicating pipes or connections, and the space at 30 the back of the radiator being perforated, somewhat honey-comb like, by means of a series of short horizontal pipes or ducts by which the air was directed on to the parts to be cooled.

35 The object of my present invention is to provide a radiator or cooler in which the maximum, cooling surface is disposed directly about the course taken by the current of air drawn into, circulated round, and 40 driven out of, the cooling chamber.

The invention consists essentially in providing at the front and back of the radiator an additional annular chamber concentric with the axis of the fan, and from which radiate a series of tubes connected at their outer ends with a larger concentric chamber divided diametrically by partitions into two compartments, and having communicating pipes or passages from the main annular chamber, so that the water to be cooled is caused to flow from the upper compartment of said concentric chambers through the upper half of the series of radial tubes to the inner annular chambers, and thence through

the lower half of the radial tubes into the 55 lower compartment from which it discharges into the body of the radiator and circulates about the main annular chamber.

In order that my invention may be better understood reference will be made to the accompanying drawings, which are in illustration of a radiator or cooler constructed in accordance with the present improvements and suitable for use upon an ordinary motor car.

Figure 1 is a front elevation with part of 60 the right hand half broken away or in section for the sake of clearness. Fig. 2 is a similar view to Fig. 1, but taken from the back of the radiator. Fig. 3 is a transverse vertical section taken through the main annular chamber of the radiator, and Fig. 4 is a 70 central sectional elevation through the entire device but taken at right angles to Fig. 3.

Like letters of reference indicate the same parts in the various figures, and it may be 75 here noted that the thicknesses of sheet metal from which the radiator is made have been somewhat exaggerated for purposes of clear illustration.

80 a is the main annular chamber supported upon the base or tank b and into which the water to be cooled from the motor is forced through a pipe c, Figs. 2 and 4, by means of a circulating pump of any well known form and not shown in the drawings.

85 d (Fig. 2) is the discharge pipe from the base or tank b and from which the cooled water is returned to the engine cylinders or other parts of the motor for fresh use, a constant circulation being thus maintained and 90 frequent changing or replenishing of the water obviated.

In the form of my invention illustrated I preferably form the inner surface e of the annular chamber a from corrugated sheet 95 metal so that an increased cooling surface is insured.

The annular chamber a is open at its lower part to the base or tank b and is stopped-off at its upper part by means of partitions f, f, 100 Fig. 3, so that the warm water as it rises in said chamber is further cooled by circulating about the corrugated surface e. Short pipes g, g, are fitted to each partition f, f, to permit of the egress of air contained in the tank 105 b or chamber a to the space in the crown a' above the normal level of the water in the radiator, and from which it escapes through

the vent h in the removable cap i , said vent h also serving as an escape for any steam that should accumulate in the radiator.

j is the loose end plate or cover for the front of the radiator which is made with double walls to form an additional annular chamber k concentric with the axis of the spindle l of the fan m . Extending from this chamber k are a series of flat tubes n, n . Said tubes n, n , may be of any cross-section and arranged in any suitable manner, but I prefer that shown. I wish it understood, however, that I in no way restrict myself to any number of radial tubes, as they may be increased or decreased according to their cooling capacity and also to suit different conditions of working. These tubes n, n , are connected at their outer ends with a larger concentric chamber divided diametrically into upper and lower compartments j' , j'' by partitions j^1, j^2 , Fig. 1.

j^1, j^2 are short pipes connecting the cover j respectively with the inlet pipe c and the base or tank b .

In order that proper connection and disconnection of the cover j to the radiator may be readily effected, I provide the pipes j^1, j^2 with flanges arranged to be secured to the cover j by means of screws j^3, j^4 , and in order to allow for the free passage of the water to be cooled to and from both sides of said flanges I form the cover j with an annular hollow rib j^5 as will be clearly understood on reference to Figs. 3 and 4 of the accompanying drawings.

o is the end plate or cover for the back of the radiator and it is made somewhat similar to the front cover j , but is not detachable.

o' is an annular chamber of large capacity concentric with the spindle l of the fan m , and p, p are flat tubes similar in cross-section to the tubes n, n employed in connection with the front cover j and which connect radially with an outer concentric chamber divided into two compartments o^2, o^3 , by means of partitions o^4, o^5 , Fig. 2. The number and cooling capacity of tubes p, p may be considerably varied as explained in reference to the front cover j . The upper compartment o^2 communicates with the supply from the inlet pipe c through an opening or aperture o^6 , Figs. 2 and 4, and the lower compartment o^3 opens directly at its lower part into the base or tank b through an opening o^7 .

q, q are ball bearings suitably connected with the plates or covers j and o and in which the spindle l of the fan m is adapted to freely revolve, said spindle l being set in revolution by any convenient means, such for instance as a belt passing over the pulley r and driven from any suitable part of the motor.

s , Figs. 3 and 4, is an outlet—normally closed by means of a sliding plate t —connecting the fan chamber at its lower part with the outlet air for the purpose of allowing grit

or other material drawn into the radiator to be removed and thereby obviating any possibility of damage to the fan, and also for regulating the supply of air to the fan according to the outside temperature.

u is a drain aperture closed by a screwed plug for draining off the water when the radiator is not in use, and v is an overflow pipe.

w is a loose cap screwed into the end of the spindle l to prevent dust working into the front bearing q .

In use, the fan m is set in revolution by means of a belt passing over the pulley r and heated water from the motor is forced into the radiator through the pipe c , said water being divided into two parts, one flowing through the short pipe j^1 into the upper compartment j' at the front of the radiator, and the other part passing through the opening o^6 into the upper compartment o^2 at the back of same. Both volumes of water are then directed by means of the partitions j^2 and o^4 through the upper series of flat tubes n and p into the central annular chambers k and o' from which it respectively flows through the lower series of tubes n and p into the lower compartments j'' and o^3 and thence into the base or tank b and main annular chamber a from whence it is returned to the parts to be cooled through the discharge pipe or outlet d . The water in its passage thus becomes thoroughly cooled by circulating through the various chambers and circulating pipes before it reaches the return pipe d consequent upon the constant flow of cool air through the device, cool air at the same time being drawn through the radiator and driven out between the pipes p, p on to the motor and parts to be cooled thereby greatly assisting in keeping down the temperature of parts liable to become overheated.

By my present invention I find that the water is cooled in a more thorough and effective manner, a more constant temperature is maintained under variable working conditions, less water is required, and greater economy insured, while free access is provided for purposes of cleaning and lubrication, better results are attained and the apparatus is cheaper to manufacture and not liable to get out of order.

The details of construction and arrangement of parts may be varied more or less as may be found desirable without in any way departing from the nature of the invention.

What I claim as my invention, and desire to secure by Letters Patent, is:—

1. In radiators or coolers, for motor-road vehicles having an air propelling fan said radiator being provided with an axis and a main annular chamber, in combination with means providing additional small and large annular chambers concentric with the axis of said fan, and disposed at the back and front

of the radiators, with a series of tubes radiating from said small chambers, and connected at their outer ends with said large chambers, partitions dividing said large chambers into 5 two compartments and communicating pipes or passages from the said main annular chamber, so that the water to be cooled is caused to flow from the upper compartments of said larger concentric chambers through 10 the upper half of the series of radial tubes to the inner annular chambers, and thence through the lower half of the series of radial tubes into the lower compartments from which it flows into the base of the radiator 15 and circulates about the main annular chamber, as set forth.

2. In radiators or coolers for motor road vehicles of the kind hereinbefore described, a detachable end plate or cover for the front of 20 the radiator consisting of an annular chamber concentric with the axis of the fan and from which radiates a series of tubes connected at their outer ends with a larger concentric chamber divided diametrically by 25 partitions into two compartments and having communicating pipes or passages from the main annular chamber, substantially as described and shown.

3. A radiator or cooler for motor-road vehicles having an air propelling fan, said radiator being provided with an axis, and a main annular chamber, and at the back of the radiator with two other annular chambers, concentric with the said axis of the fan, and provided with a series of pipes connected at their inner ends with one of said concentric chambers and at their outer ends with an other concentric chamber, the latter being formed integrally with the said main annular chamber, and provided with partitions dividing said chamber into two compartments and having communicating passages, substantially as described. 30 35 40

4. A radiator or cooler for motor road vehicles, provided with a main annular chamber having a corrugated inner surface, combined with a plurality of short pipes for the escape of air from said chamber, and a removable cap *i* provided with a vent *h*, substantially as described and shown. 45 50

In witness whereof I have hereunto set my hand in the presence of two witnesses.

FRIEDRICH JOHANN DITRICH HÜLLINGHORST.
